UNITED STATES PATENT OFFICE.

PATRICK A. BAYLESS, OF MINNEAPOLIS, MINNESOTA, ASSIGNOR OF ONE-HALF TO
HOMER RAY, OF MINNEAPOLIS, MINNESOTA.

SCRUBBING AND MOPPING BRUSH.

1,215,239.

Specification of Letters Patent.

Patented Feb. 6, 1917.

Application filed May 2, 1916. Serial No. 94,961.

To all whom it may concern:

Be it known that I, PATRICK A. BAYLESS, a citizen of the United States of America, residing at Minneapolis, in the county of 5 Hennepin and State of Minnesota, have invented certain new and useful Improvements in Scrubbing and Mopping Brushes, of which the following is a specification, reference being had therein to the accompanying 10 drawing.

This invention relates to brushes and has special reference to a scrubbing and mopping brush.

The principal object of this invention is 15 the production of a simple and efficient means for detachably holding the brush in engagement with the brush holder.

Another object of this invention is the 20 production of a simple and efficient mopping device carried by the brush holder wherein the water may be forced up into a container formed upon the brush holder.

With these and other objects in view this 25 invention consists of certain novel combinations, constructions, and arrangements of parts as will be hereinafter fully described and claimed.

In the accompanying drawings:—

Figure 1 is a perspective view of the scrubbing and mopping brush.

Fig. 2 is a central vertical section thereof showing the device used as a mop.

Fig. 3 is a top plan view of the brush holder showing the brush removed therefrom.

Fig. 4 is a detail perspective view of the inner portion of the brush holder showing the brush removed therefrom.

Fig. 5 is an end view of the device in operation.

Fig. 6 is a bottom view of the mop holder showing the manner in which the mopping strip is supported in engagement with the holder.

Fig. 7 is a perspective view of the clamping strip for holding the mopping strip in position.

By referring to the drawings it will be 50 seen that 1 designates the main plate of the brush holder which is provided with an upwardly extending flange 2 having an in-turned lip 3, which lip 3 is adapted to fit under one side edge of the brush 4 as illustrated clearly in Figs. 1, 2 and 5 of the 55 drawings. The main plate 1 carries a me-

tallic sleeve 5, which sleeve is adapted to receive a handle 6 of any suitable or desired construction. The plate 1 also carries a water receiving receptacle 7, which receptacle is provided with a laterally extending flange 8 for facilitating the securing of the receptacle 7 to the main plate 1. The water receiving receptacle 7 comprises an elongated trough-like structure having one closed end 9 and a water discharge end 10. 60 The water discharge end 10 is provided with a water discharge aperture 11 formed therein to facilitate the emptying of the water from the water container 7 when so desired. The water container 7 is provided at its 70 free edge with an inwardly extending flange 12, which flange tapers toward the center of the container. The container 7 is elevated toward the center thereof as indicated by the numeral 13 and slopes slightly toward each end of the container so as to 75 constitute a substantially V-shaped support for the mopping strip 14 adapted to be supported thereon.

A plurality of brush supporting feet 15 80 are secured to the main plate 1, and these supporting feet 15 are provided with projecting flanges 16 having inturned edges 17 for firmly engaging one side edge of the brush and firmly holding the brush upon 85 the brush holder.

An angle strip 18 is secured to the inner face of the water container 7 near the rear wall thereof and is provided with a plurality of projecting lugs 19, the lugs 19 being 90 provided with apertures 20 formed therein for the purpose of receiving the securing pins 21 adapted to be placed therethrough for holding the mopping strip 14 firmly upon the lugs 19. The mopping strip 14 is 95 provided with a plurality of apertures formed therein for the purpose of fitting over the lugs 19. It will, therefore, be seen that the lugs 19 will constitute an efficient supporting means for the mopping strip 14. 100 It should be borne in mind that the strip 14 is preferably formed of flexible rubber of suitable stiffness or thickness to prevent the same from being bent backwardly upon itself. The strip, however, is sufficiently 105 yieldable to allow the same to be moved slightly away from the edge 22 of the water container 7 in order that the water mopped by the device may be drawn up into the water container 7. It should be further un- 110

derstood that the flanges 12 are bent inwardly at an angle of substantially 45° as clearly illustrated in Fig. 2 to permit the water while rising to pass into the container 7 and at the same time prevent the water from being removed or accidentally dropped from the container between the edge of the container and the mopping strip 14.

- 10 A retaining strip 23 is employed for the purpose of holding the mopping strip 14 in place, and this retaining strip carries the integral pins 21 above described which are slightly bent outwardly at the inner ends 15 thereof as clearly illustrated in Fig. 7. This strip 23 is formed so as to conform to the contour or shape of the inner edge of the water container 7, that is to say being bowed slightly in the center thereof as indicated by 20 the numeral 24. The strip 23 is also bowed slightly upwardly as indicated at 25 to constitute a reinforcing corrugation near the end of the strip just above the end pins 21 carried thereby. The strip 23 is formed of 25 sheet metal and is bent backwardly upon itself to constitute a reinforcing flange 27 along the body of the strip 23.

Having thus described the invention what is claimed as new, is:—

- 30 1. A device of the class described comprising a body, a water receiving receptacle secured thereto, said receptacle comprising an elongated body being inclined toward each end thereof, said receptacle provided 35 with an inwardly extending flange constituting a water containing flange, and a flexible mopping strip secured to said water receiving receptacle.

- 40 2. A device of the class described comprising a body, a water receiving receptacle secured thereto, said receptacle comprising an elongated body being inclined toward each end thereof, said receptacle provided with an inwardly extending flange constituting a water containing flange, said receptacle provided with a lug supporting flange, lugs secured to said flange, a flexible mopping strip, and means engaging said lugs and also engaging said mopping strip for 45 firmly holding said mopping strip upon said water receiving receptacle.

- 50 3. A device of the class described comprising a body, a water receiving receptacle secured thereto, said receptacle comprising an elongated body being inclined toward each end thereof, said receptacle provided with an inwardly extending flange constituting a water containing flange, a flexible mopping strip secured to said water receiving 55 receptacle, said water receiving receptacle provided with projecting lugs formed thereon, said lugs provided with apertures

formed therein, a flexible mopping strip fitting over said lugs, and a metallic clamp engaging said lugs and fitting against said 65 mopping strip for firmly holding said mopping strip upon said lugs.

4. A device of the class described comprising a body, a water receiving receptacle secured thereto, said receptacle comprising 70 an elongated body being inclined toward each end thereof, said receptacle provided with an inwardly extending flange constituting a water containing flange, a flexible mopping strip secured to said water receiving 75 receptacle, said water receiving receptacle provided with projecting lugs formed thereon, said lugs provided with apertures formed therein, a flexible mopping strip fitting over said lugs, a metallic clamp engaging said lugs and fitting against said 80 mopping strip for firmly holding said mopping strip upon said lugs, said metallic clamping member comprising an elongated body having a rolled edge along one side 85 thereof, a plurality of pins carried by said clamping member and fitting in said apertures of said lugs for firmly holding said mopping strip upon said water receiving receptacle. 90

5. A device of the class described comprising a body, a water receiving receptacle secured thereto, said receptacle comprising an elongated body being inclined toward each end thereof, said receptacle provided 95 with an inwardly extending flange constituting a water containing flange, a flexible mopping strip secured to said water receiving receptacle, said water receiving receptacle provided with projecting lugs formed 100 thereon, said lugs provided with apertures formed therein, a flexible mopping strip fitting over said lugs, a metallic clamp engaging said lugs and fitting against said mopping strip for firmly holding said mopping strip upon said lugs, said metallic clamping member comprising an elongated body having a rolled edge along one side 105 thereof, a plurality of pins carried by said clamping member and fitting in said apertures of said lugs for firmly holding said mopping strip upon said water receiving receptacle, and said clamping bar provided with bulged portions struck therefrom for producing a 110 spring clamp for holding said flexible mopping strip in engagement with the inner edge of said water receiving receptacle. 115

In testimony whereof I hereunto affix my signature in presence of two witnesses.

PATRICK A. BAYLESS.
